SLIP COVER

Lionel C. Lenz, Chicago, Ill., assignor to
Sam Pass, Chicago, Ill.

Application December 9, 1950, Serial No. 200,000

1 Claim. (Cl. 155—182)

This invention relates to slip covers for use on overstuffed chairs and davenport's for example.

Generally, ready made slip covers of the types presently available are provided with separate bag-like compartments for the removable cushions of articles of furniture of the character mentioned and require the insertion of the cushions in the compartments. For the purpose of avoiding the formation of wrinkles in the upper panels of the cushion compartments, the same generally are dimensioned to provide a rather snug fit which requires the exertion of considerable effort on the part of the user in inserting a cushion without twisting the cover compartment to an awry relation with respect to the cushion. Likewise, it is sometimes rather difficult to remove the cushions from the cover compartments when the latter are to be laundered. Generally, such cushion cover compartments are provided with drawstrings or the like at the rear open ends to enable the free edges of such ends to be drawn to a closed or semi-closed condition for retaining the upper rear edge of the covers in concealed position while the cushion covers are in use on the articles of furniture.

It is an object of the present invention to provide an improved slip cover which reduces the effort required in, and avoids the annoyance usually accompanying, the placement of conventional slip covers in position on articles of furniture of the type referred to, particularly with respect to the cushion covering elements of such covers. While the provision of cushion covering panels or compartments as attached parts of slip covers has been heretofore resorted to, the present invention provides a novel slip cover provided with a cushion covering portion as an integral part of the section of the cover which facilitates placement of the cover in position on an article of furniture as well as the removal of the cover and which presents a neat, fitted appearance while in use.

Another more specific object of the invention is to provide a slip cover which embodies a cushion covering portion as an integral part of the cover or of a cover section and having means for engaging the cushion along the rear end and sides for releasably retaining the cushion covering portion in proper position on the cushion while in use.

An additional object of the invention is to provide a slip cover comprising a section formed of connected portions or panels for covering the arms, the cushion, the sides of the article of furniture and the front thereof, such as a chair, and a second cover section for the back rest of the article, which latter section may be separate from or connected to the other section, but in either event the two sections are so arranged that easy access to the rear of the cushion is provided to enable the cushion cover portion to be secured readily to the cushion while the same rests, at least in part, on the cushion base or seat of the article.

By means of the present invention, the improved slip cover can be placed in position without complete removal of the cushion from the article of furniture, since no bag-like compartments for the cushion is provided, but on

2

the contrary, the cushion covering portion of the cover is provided with retaining means which can be placed in position on the cushion while the latter lies in normal position or if preferred, can be placed in position after tilting the rear of the cushion upwardly from contact with the forward portion of the back rest of the article of furniture.

The advantages of the novel slip cover as adverted to above will be apparent from a consideration of the following specification and accompanying drawings which disclose a slip cover embodying the present improvements.

In the drawings:

Figure 1 is a perspective view of a conventional club chair, viewed generally from the front, with a slip cover embodying the present invention thereon, parts of the cover being broken away to reveal the associate parts of the chair;

Fig. 2 is a perspective view of the chair and cover viewed from the rear, portions of the cover being shown unsecured in final position for clarity of understanding of the preferred arrangement and overlapping of the parts;

Fig. 3 is a broken perspective view of the slip cover with the parts in the same relative positions shown in Fig. 1, but without illustration of the chair shown in the latter figure;

Fig. 4 is a perspective view of the section of the cover which covers the arms, seat, and front of the chair, no chair being shown;

Fig. 5 is a perspective view of the section of the cover which covers the chair back rest, the section being unattached to the section shown in Fig. 4;

Fig. 6 is a broken perspective view of a cushion covering portion of the improved cover in position on a cushion which is shown fragmentarily and with the cushion and cushion covering portion in an inclined position; and

Fig. 7 is a broken enlarged view illustrating an elastic tape employed at the lower edge of the cushion cover portion.

The particular cover shown in the drawings is of the two-section type, such as is illustrated in Patent No. 2,459,328 granted to me January 18, 1949, for Slip Cover. However, as will be apparent from the following description, the present improvements may be utilized in unitary or one-piece covers, that is, covers wherein the parts are secured together as a unit rather than made in independent sections as in the patent mentioned.

The improved cover selected for the purpose of illustration is designed for use on a club chair, but the improvements can be embodied in covers for chairs of other styles or for davenport's provided with removable seat cushions. Hence, it should be understood that the following description of details of the illustrated cover is for the purpose of completeness of disclosure and not as a limitation of the improvements to covers for articles of furniture of a particular style.

In Figs. 1 and 2 of the drawings, the improved cover is shown having parts shaped to conform to and cover corresponding portions of the chair which generally consists of a base portion supported by forward legs 10 and rear legs 11, arms 12, a seat or cushion support 13 located between the arms, a removable cushion 14 and a back rest 15.

The improved cover comprises two sections designated generally A and B. Section A is the back rest cover section which in the illustrated embodiment of the invention is made separate from section B. Briefly, section A comprises a forward panel 16 for covering the front of the back rest 15, shoulder panels 17 and a rear panel 18 all secured together to provide an inverted bag-like compartment adapted to be drawn downwardly over the back rest of the chair to cover the same. The panel 16,

as viewed in Figs. 3 and 5 is provided with sufficient material 19 at the free lower end to enable the same to be tucked into the space between the lower portion of the back rest 15 and the rear end of the adjacent cushion 14 for retention of that portion of the panel 16 in place during use. The lateral sides of the panel 16 are adapted to be tucked into the crevices or spaces between the back rest and the rear of the arms. The seam 20, by means of which the rear panel 18 is secured to the forward panel 16 and shoulder panels 17 of the section A preferably is of the piping or tubular type and extends to the lower end of the panel 18 for accommodating a drawstring 21, the lower ends of which extend from the piping and can be attached to the rear legs 11 of the chair. Advantages of the drawstring construction just briefly described are more fully set forth in Patent No. 2,392,051 granted to me January 1, 1946 for Slip Cover.

The cover section B comprises connected parts or panels for covering the arms, sides, front and cushion of the chair. For example, the section B illustrated comprises a front panel 22, forward or face panels 23, 23, side panels 24, 24 which cover the sides of the chair and extend up over the arms 12 and thence downwardly, as inner panels 25, 25, along the inner surfaces of the arms to approximately the level of the cushion support or seat 13 where they are joined, by seams later described, to a cushion cover portion. The cushion cover portion is indicated generally by numeral 26 and comprises a top panel 26a, a front panel 26b, side panels 26c and a rear panel 26d which are sewed together at the contiguous ends to provide an inverted box-like enclosure, open at the bottom, for the cushion 14.

The lower edge of the front panel 26b is stitched to the upper edge of the front panel 22, or those two panels can be formed of a single piece of material if desired. The lower edge of each side panel 26c is stitched to the lower edge of the inner arm cover panel 25 as indicated by numerals 27, 27. An elastic member or tape 28 extends along or partially along the lines of stitches or seams 27, 27 and across the lower edge of panel 26d, and is confined in position as by overcast stitches 28a as indicated in Fig. 7, which stitches permit the elastic to elongate and contract. The ends of the elastic tape are anchored to the side seams 27 with the tape in a stretched or elongated condition, whereby the contraction of the tape effects a gathering of the material along the tape as the elastic contracts when the stretching force is released. In Figs. 3 and 6, the ends of the elastic tape are shown as anchored along the seams 27, 27 at points 29, 29, but these points may be located farther toward the front or rear of the cushion by employing longer or shorter tapes as desired. The purpose of using the elastic tape along the lower edge of rear panel 26d and along the lower edges or portions of the edges of the side panels 26c is to cause those edges to tend to contract and grip to rear and side walls of a cushion when the panels 26a, 26c and 26d have been distended in drawing said panels down along the cushion walls. The rear panel 26d preferably is of adequate vertical dimension to enable it to be drawn manually slightly under the rear edge of the cushion as indicated in Fig. 6 as the cushion cover portion is placed on the cushion whereby the tension exerted by the elastic tape 28 retains the rear of the cover portion 26 in place and resists displacement and disarray of the top panel 26a during use.

In placing the cover sections A and B on an article of furniture, the section B may, if desired, be applied first by drawing the arm cover portions down over the arms of the article and drawing the rear ends 24a of the side panels 24, 24 to the rear of the article and securing them by the tie strings 30 or other appropriate fasteners. The cushion cover portion 26 can be placed in position by tucking the side panels 26c, 26c and rear panel 26d down along and partially under the respective walls of the cushion, but it has been found more convenient first to

elevate the cushion at the rear end, as shown in Fig. 6 when the side panels 26c and the rear panel 26d can be drawn downwardly to locate the elastic tape 28 along the lower edge of the rear of the cushion or preferably to locate the tape slightly beneath or forwardly of the lower edge of said rear wall along the bottom surface of the cushion as shown in said figure and then restoring the cushion to its proper position. The elastic tape is of such length that elongation thereof is required in so fitting the cover portion 26 to the cushion and hence offers considerable resistance to the displacement of the portion from the described gripping relation on the cushion.

The rear edges of the inner arm cover panels 25 are adapted to be tucked into the crevices or spaces 31 between the rear of the arms and the back rest. After section B has been placed in position, as described, the section A may then be drawn down into position over the back rest and the ends of the drawstring 21 secured to the rear legs in taut condition. The surplus material 19 at the lower end of forward panel 16 is tucked into the space between the lower portion of the back rest 15 and the rear end of the cushion 14. The rear panel 18, as indicated in Fig. 2, preferably overlaps the rear end portions 24 of the side panels 24. A strip of pleats 32 preferably is provided along the lower edge of the section B which is stitched to the section along the front of the section and rearwardly along the sides to positions short of the rear legs, the remaining portions of the strip being free and adapted to be overlapped at the rear of the chair and secured in position by means of upholstery pins or the like to provide a neat, finished appearance at the rear of the article.

While the upholstered cover is of the two section type, the sections may be combined, if desired, to provide a unitary or one piece slip cover without departure from the described invention. For example, the cover sections A and B can be secured together by stitching the portions of lower edges of the shoulder panels 17 of section A to portions of the rear edges of the arm cover panels 24, 25 of section B which meet at the upper surface of the rear of the arms in the illustrated cover. In such a one piece cover the free lateral edges of the forward panel 16 of section A which extend below the level of the shoulder panels 17 are left free for tucking into the vertical spaces 31 between the rear of the arms of the article and the contiguous portion of the back rest, as in the two section cover shown in the drawing, and the lower end of the forward panel 16 will likewise be free and of adequate length to be tucked down at the rear of the cushion as above described. Thus in either form of slip cover, the inverted box-like cushion cover portion 26 is unattached at the rear to the forward panel 16, and fits down over the cushion and is retained in position on the cushion by the elastic insert or tape 28 described above, thereby avoiding the use of a cover panel beneath the cushion as well as a separate cushion compartment or bag-like enclosure usually constituting an accessory of the conventional one piece slip cover.

While I have shown and described a slip cover embodying the invention in its preferred form, it will be apparent that changes in the details of the cover proper may be resorted to without departure from the spirit of the invention defined by the appended claim.

65 I claim:

A slip cover for an article of furniture having a seat, arms, back rest and a removable cushion for the seat, said slip cover comprising a front covering portion, arm covering portions and a cushion covering portion, said cushion covering portion comprising a top panel and front, side and rear panels secured to and depending from top panel and connected together along the vertical edges thereof to define with said top panel an inverted box-like compartment adapted to be drawn over a seat cushion, said side panels having lower edges extending long-

tudinally and disposed entirely within a substantially horizontal plane formed by a cushion bottom, said lower edges of the side panels each being connected to the corresponding adjacent portions of the arm covering portions, said front panel being connected along the lower edge thereof to said front covering portion, the lower edge of said rear panel being free, and an elastic tape attached to and extending along the entire lower free edge of said rear panel and attached to and extending substantially along the greater part of the length of each lower edge 10 of said side panels and having each end of the tape anchored to the corresponding adjacent lower edge of said side panels at points near the front of the box-like compartment thus requiring initial stretching of said elastic tape when the box-like compartment is drawn downwardly 15 over a cushion.
